ATTORNEY

UNITED STATES PATENT OFFICE.

GARLEN I. SNYDER, OF INDIANAPOLIS, INDIANA.

PAPER HOLDING AND ADVANCING MECHANISM.

Application filed June 19, 1926. Serial No. 117,204.

My said invention relates to paper holding and guiding devices and it is an object of the invention to provide compact and portable means for holding and adjusting one or more sheets of paper bearing printed or written matter in a manner to facilitate reading and copying of such matter by an operator on a typewriter or by hand.

Another object of the invention is to provide a device of this character operable in a manner similar to the conventional typewriter for inserting the paper, alining the print and advancing the paper line-for-line through the machine.

15 Referring to the accompanying drawings which are made a part hereof and on which similar reference characters indicate similar parts,

Figure 1 is a perspective of my invention, 20 Figure 2, an end view,

Figure 3, a detail on the line 3—3 of Figure 2,

Figure 4, a fragmentary detail of a pair 25 of cooperating rollers,

Figure 5, a top plan view, partly in section,

Figure 6, a section on line 6—6 of Figure 5,

Figure 7, a fragmentary detail section on 30 the line 7—7 of Figure 6,

Figure 8, a fragmentary end elevation illustrating the advancing mechanism,

Figure 9, a fragmentary detail section on the line 9—9 of Figure 8,

35 Figure 10, a fragmentary detail front elevation of the advancing mechanism, and

Figure 11, a section on line 11—11 of Figure 6.

In the drawings reference character 10 indicates a housing or frame of the device in which is mounted a shaft 11 which supports a cylinder or roller 12 formed of rubber or other relatively soft gripping material. The shaft 11 is provided on its outer end with an operating knob 13 and a friction clutch disk is also mounted on said shaft between the operating knob and the end of the cylinder 12. A lever 16 has one end loosely mounted on the shaft 11 between the hubs of the knob 13 and disk 14 upon the intermediate portion of which lever is mounted a screw 17 that forms a pivotal support for a gravity operated clutch member 18 provided with a slot 19 to engage the rim 15 of the clutch disk 14. The clutch member 18 is relatively

thin at its slotted portion to affect the operation of gripping or binding the rim 15 and is provided with a thickened portion 20 to assist in the gripping action by reason of its added weight.

60 The lever 16 is provided at its outer end with a pivot 21 to which is connected one end of a link 22, the other end of said link being connected to a pivot 23 carried by the offset extremity 24 of a rocker bar 25. Said 65 rocker bar 25 is mounted on pivots 27 and is provided with a strike bar 26 which is adapted to be depressed for elevating link 22 and lever 16 to cause the clutch member 18 to grip the rim 15 of the clutch disk 14 and 70 rotate the same and the shaft 11 upon which it is supported as well as the cylinder 12 mounted on said shaft. To aid and insure the operating mechanism returning to its original position a spring 28 is provided, one 75 end of which extends through a hole 29 in the link 22 and the other end of the spring extends through a boss or lug 30, said boss or lug also serving as a stop for limiting the downward movement of the link 22 and lever 16 as well as the upward movement of the bar 26.

80 In order that the upward movement of the lever 16 may be varied and adjusted to the various line spacings found on printed matter an adjusting hub 31 is provided said hub having an operating knob 32 adapted for contact with portion 33 of the rocker bar 25, said hub and knob being carried on a threaded stub 34 which projects through a vertical 85 slot 35 in the housing 10. I provide the screw 34 with flattened side portions 36 adapted to fit in the slot 35 and prevent the screw from turning when the knob is rotated to tighten the same in position.

90 The housing 10 is provided with an opening 37 extending longitudinally across the same and below said opening and the roller 12 is provided a pan or guide 38 having attached thereto a bar 40 which extends longitudinally of the guide and is provided with inturned ends 41 supported by pivots 39 in the form of screws extending through the ends of the housing 10. The guide 38 is provided with bearings 42 in which is mounted 95 a small roller 43 of material similar to cylinder 12 and adapted for co-operation with the cylinder 12 for holding paper in position. In order to cause the roller 43 to bear against the roller 12 the guide or pan 38 is provided 100 105 110

with a flange 45 to which the upper ends of springs 44 are attached, the lower ends of said springs being secured to a bar 46 supported by means of adjusting screws 47 extending through the bottom of the housing. The adjusting screws may be operated for varying the tension on the springs 44 whereby the pressure of the roller 43 against the cylinder 12 may also be varied.

10 The free end 48 of the guide 38 extends upwardly beyond the roller 43 and is bent slightly inwardly toward the cylinder 12 to aid in guiding the paper under a plate or straight edge 49 pivoted at 50 within the housing 10 so that it will rest, on account of its own weight, with its upper edge against the paper regardless of the thickness of the same or whether one or several sheets are inserted.

20 Pressure releasing means is provided for releasing the pressure of the roller 43 against the cylinder 12 in order that paper may be readily inserted and alined in the holder. Said means comprises a cam or laterally bent portion 51 of a longitudinally disposed shaft 52 which is mounted behind the guide or pan 38, said shaft being pivoted at one end in boss 53 and at its other end on screw pivot 54. The end of shaft 52 extends laterally 30 through the casing and forms a handle 55 by means of which when the same is pulled forward, as shown by dotted lines in Figure 6, the offset portion of cam 51 will bear against the guide 38 and move the same laterally on its pivots 39 against the tension of the springs 44 until the cam 51 has passed beyond a line between the centers of the shafts 11 and 52 where it will remain until the handle is again manipulated to bring 40 parts to their original positions.

45 A roller 56 of material similar to the rollers 12 and 43 is mounted on arms 57 supported on pivots 58 on the housing, said arms being pulled downward by springs 59 causing the roller 56 to bear against the upper portion of the cylinder 12 in order to hold the paper after it is fed downwardly around the roller 12 and upwardly past the roller 43 and plate or straight edge 49.

50 A cam 60 is supported by a pivot 61 on one of the arms 57, one end of the cam being provided with a manipulating extension or tab 62 by means of which the roller may be swung backwardly to the position shown in Figure 2 where it is out of the way or the cam may be swung on its pivot until the inner end 63 of the tab 62 bears against the arm 57, as shown by dotted lines in Figure 2. It will be noted that when a sheet of 60 paper has been inserted in the machine and advanced past the roller 43 the paper will still be held in place by roller 56 and a straight edge or plate 49 which permits the last line to be held in properly alined position to be read.

It is desirable to have the cylinder 12 freely rotatable in either direction while the paper is being inserted and adjustable at all times except when the strike bar 26 is manipulated for advancing the paper through the machine, and since the gravity operated clutch 18 would normally prevent reversing the cylinder on account of its relation to the rim 14 I provide an adjustable release screw 64 mounted in a boss or lug 65 on the housing 10 adapted to be adjusted so that it will just hold the clutch member 18 in a position sufficiently elevated to prevent the same from binding upon the rim 15 when the lever 16 is in its normal position, as indicated in full lines in Figure 8.

When the strike bar 26 is depressed to lift the lever 16 the pivot 17 upon which the clutch member 18 is mounted will be elevated and the free weighted end 20 will be lifted off of the screw 64 and will grip and rotate the rim 65 and the cylinder 12. The gravity operated clutch member fits snugly on the rim 15 and there is little lost motion introduced by the release, said lost motion remaining constant will have no effect on the spacing. In order to enhance the wearing qualities the clutch member 18 is preferably formed of harder material than the rim 15.

55 In the operation of the device the paper bearing the printed matter or the like to be copied is inserted downwardly through the slot 37 and between the guide 38 and the cylinder or roller 12 around the cylinder and upwardly past the roller 43 whereupon turning of the knob 13 to rotate the cylinder 12 in the direction of the arrow will advance the paper upwardly past the plate or straight edge 49 until the line of print is visible and the upper edge of the paper is caught beneath the roller 56, said roller being elevated by manipulating the lever 62, whereupon the strike bar may be depressed for advancing the paper line-by-line through the machine.

60 In order to adjust the device to the spacing of the lines on the paper the paper is inserted as just described and the strike bar is again depressed until the next line of print is visible above the plate 49. While the strike bar is thus held in depressed position the knob 32 is loosened and moved until its upper portion 31 contacts with the portion 33 of the rocker bar 25. Whereupon the knob is re-tightened thereby limiting thereafter the amount of upward movement imparted to the link 22 and bar 16 until further adjustment becomes desirable.

65 It will be obvious to those skilled in the art that various changes may be made in my device without departing from the spirit of the invention and therefore I do not limit myself to what is shown in the drawings and described in the specification but only as indicated in the appended claim.

Having thus fully described my said invention, what I claim as new and desire to secure by Letters Patent, is:

The combination of a rotary element having a laterally extending rim, a lever mounted concentrically of said rim and extending beyond the periphery of the same, a clutch member mounted on said lever and having a slot receiving said rim, comprising means for oscillating the lever to rotate the rim, a manually operable lever spaced from

said first-mentioned lever, a link connecting said levers, an adjustably mounted stop for limiting the stroke of the manually operable lever, and a lug for limiting the downward movement of the link, substantially as set forth. 15

In witness whereof, I have hereunto set my hand at Indianapolis, Indiana this 14th day of June, A. D. nineteen hundred and 20 twenty-six.

GARLEN I. SNYDER.
